UNITED STATES PATENT OFFICE.

ANTHONY W. BELL, SR., AND HARVEY L. JENNINGS, OF UNIONTOWN, PENNSYLVANIA.

TIMBER HOIST.

Application filed October 5, 1926. Serial No. 139,660.

The present invention relates to improvements in lifting devices, and is more particularly adapted to an apparatus for hoisting timbers or cross bars in coal mines and 5 for supporting the timber in its raised position adjacent the ceiling of the mine while the leg members are being positioned beneath the respective ends of the timber or cross bar.

10 At the present time, considerable time and labor is spent in manually lifting the timber or cross bar for holding the same in position until the leg members are put under the same in a coal mine and the present invention has for its object to provide a device which will save considerable time and labor in handling these timbers or cross bars in a coal mine.

15 A further object of the invention is to provide a timber hoist of the above mentioned character which includes a vertically movable carriage on which is adapted to rest in a horizontal position the timber or cross bar, means being provided for actuating the carriage for moving the timber to its proper position.

20 A still further object is to provide a timber hoist which is of such construction as will enable the same to be readily set up in position within a mine, the hoist including a ceiling engaging head which will provide for a rigid structure and thus insures the proper operation of the apparatus when in use.

25 A further object is to provide a timber of the above mentioned character which is simple in construction, inexpensive, strong and durable, and further well adapted to the purpose for which it is designed.

30 Other objects and advantages of the invention will become apparent during the course of the following description taken in connection with the accompanying drawing.

In the accompanying drawing forming a 35 part of this application, and in which like numerals designate like parts throughout the several views:

Figure 1 is a side elevation of the timber hoist embodying our invention, and

40 Fig. 2 is a view taken at right angles thereto, parts of the apparatus being shown in section.

45 In the drawing wherein for the purpose of illustration is shown the preferred embodiment of our invention, the numeral 1 designates generally the lifting jack of any

well known construction, the same including a vertically movable lifting head 2 which is adapted to be raised and lowered through the medium of a suitable operating lever 3. 50 As the construction of the jack forms no important part of the present invention, a further detailed description thereof is thought unnecessary.

Our improved timber hoist comprises the 55 tubular stem or standard 4 which has its lower end secured on the vertically movable head 2 of the jack 1 so that the tubular stem or standard will be raised or lowered simultaneously with the actuation of the 60 head 2. A block-like member 5 is provided at one end with a tubular extension 6 on the bottom face thereof and said extension is adapted to fit within the upper end of the tubular stem or standard 4 as is clearly 65 shown in Fig. 2.

The portion of the block 5 directly above the tubular extension 6 is recessed to accommodate the threaded stem 7, the upper end of which carries the ceiling engaging 70 spur 8. A nut 9 is threaded on the stem 7 and is disposed within the recess formed in the block 5 for holding the stem 7 in any adjusted position. For the purpose of locking the nut 9 within the recess against accidental displacement therefrom, I provide the externally threaded ring 10 which encircles the stem 7 and is threaded into the upper portion of the recess and also engages the top face of the nut 9 in the manner 75 clearly shown in Fig. 2.

The outer end of the block 5 which extends beyond the tubular stem or standard 4 is provided with a vertical opening in which is disposed a suitable bearing 11, the 80 purpose of which will be presently apparent.

A bearing block designated generally by the numeral 12 is carried by the lower portion of the tubular stem or standard 4 and 85 in the portion of said bearing block which is disposed outwardly of the tubular stem or standard 4 there is provided a suitable bearing 13 for the lower end of the threaded shaft extending through the bushing or 90 bearing 11 provided therefor in the upper bearing block 5.

The timber supporting carriage is designated generally by the numeral 15 and the same is adapted for vertical movement along 95 the threaded shaft 14. This carriage 15 is provided with a tubular stem or standard

engaging portion 16, so that the carriage will be prevented from rotating with the shaft 14, but will be caused to move vertically on the shaft when the latter is actuated in the manner to be presently described.

roof A, and thereby permit the apparatus to be readily removed, and again positioned whenever it is necessary to install the timbers or cross bars in the mine. 60

For the purpose of actuating the screw shaft 14, we provide the transversely extending shaft 17 which is journaled through 10 suitable bearings 18 supported on the lower portion of the tubular standard 4 at diametrically opposite points. A beveled gear 19 is secured on the inner end of the shaft 17 and the same meshes with a similar gear 15 20 secured on the lower end portion of the screw shaft 14 as is clearly shown in Fig. 2. An actuating crank handle 21 is secured on the outer end of the shaft 17 and for the purpose of preventing the rotation of the 20 shaft 17 in one direction, there is provided a suitable pawl and ratchet mechanism designated generally by the numeral 22.

The use of our improved timber hoist may be briefly stated as follows:—The jack 1 is initially placed in proper position within the mine and by actuating the lever 3, the head 2 of the jack will be raised simultaneously raising the tubular stem or standard 4, and the threaded stem 7 supported in the upper end of the standard until the spur 8 carried on the upper end of the threaded stem 7 engages the ceiling A of the mine. When the platform or carriage 15 is at its lowermost position on the screw threaded shaft 14, the timber or cross bar which is to be positioned at the top of the mine adjacent the ceiling is placed on the carriage of a suitable length so as to accommodate the timber which is ordinarily of great length.

40 The crank handle 21 is then rotated in one direction so that rotary movement will be imparted through the screw threaded shaft 14, and as the shaft 14 rotates, the carriage 15 and the timber supported thereon will move upwardly until the timber has been raised to the desired height in the mine. The platform 15 will hold the timber or cross bar in its raised position so that the usual supporting leg may be placed in position underneath of the respective ends of the timber or cross bar, and after the legs and the timber spanning the upper ends of the leg members are properly positioned, the carriage or platform 15 is lowered and the jack 1 is also actuated so as to release the spur 8 from engagement with the ceiling or

roof A, and thereby permit the apparatus to be readily removed, and again positioned whenever it is necessary to install the timbers or cross bars in the mine. 60

The provision of an apparatus of the above mentioned character will save considerable time and labor in assembling the timbers and supporting legs in a mine and heretofore where it has been necessary to employ 65 five men to accomplish this work, the present apparatus will only necessitate the employment of a single person and yet will expedite the operation of raising and supporting a timber in a positive and efficient 70 manner.

While we have shown the preferred embodiment of our invention, it is to be understood that minor changes in the size, shape, and arrangement of parts may be resorted to without departing from the spirit of the invention and the scope of the appended claims. 75

Having thus described our invention, what we claim as new and desire to secure by Letters-Patent is:—

1. In a timber hoist for mines, an adjustable support, a mine roof engaging element carried by the upper end of said support, a rotatable threaded shaft arranged vertically adjacent the support and carried thereby, and a timber supporting carriage adapted for vertical movement on said shaft. 85

2. In a timber hoist for mines, an adjustable supporting standard, a mine roof engaging element carried by the upper end of said standard, bearing blocks extending laterally from said standard, a rotatable threaded shaft journaled at its ends in said blocks, means for rotating said shaft, and a timber supporting carriage adapted for vertical movement on said shaft. 95

3. In a timber hoist for mines, an adjustable supporting standard, a mine roof engaging element carried by the upper end of said standard, bearing blocks extending laterally from said standard, a rotatable threaded shaft journaled at its ends in said blocks, means for rotating said shaft, and a timber supporting carriage threaded on said shaft, the same being provided with means for engagement with said standard to prevent rotation of the carriage on the shaft. 100 105

In testimony whereof we affix our signatures.

ANTHONY W. BELL, SR.
HARVEY L. JENNINGS.
